UNITED STATES PATENT OFFICE.

CHARLES ROSAT, OF BOUDRY, SWITZERLAND, ASSIGNOR TO FABRIQUES DES MONTRES ZENITH, SUCCESEUR DE FABRIQUES DES MONTRES ZENITH GEORGES FAVRE-TACOT & CO., OF LE LOCLE, SWITZERLAND.

ASSEMBLING DEVICE FOR BRIDGES, PLATES, AND THE LIKE IN TIMEPIECE MOVEMENTS, COUNTING MECHANISMS, AND LIKE APPARATUS.

Application filed May 10, 1926, Serial No. 108,184, and in Switzerland May 26, 1925.

The present invention relates to an assembling device for bridges, plates, and the like in timepiece movements, counting mechanisms and like apparatus.

5 This device comprises, on the one hand, a setting pillar fastened in one of the two components to be assembled and freely engaging the other component and on the other hand, a combined distancing and holding 10 clasp like member formed of one and the same steel ribbon with a rolled portion pivotally arranged around said pillar to constitute a distance piece and two spring ears to constitute a clasp adapted to be turned 15 over said components.

An embodiment of this device is shown diagrammatically and by way of example in the accompanying drawing, in which

Fig. 1 is a plan view,

20 Figure 2 is a side view, looking in the direction of the arrows on the line A—A of Figure 1, and

Figure 3 is a side sectional view taken on the line B—B of Figure 1 looking in the 25 direction of the respective arrows.

Figure 4 shows in plan a development of the clasp.

The embodiment illustrated serves to assemble two plates 1 and 2; it comprises a 30 cylindrical pillar 3 engaging with one of the plates, 1 for example, into which it is simply forced and thus fixed, and with the second plate 2 into which it penetrates freely, but without play.

25 The distance piece 4 between the plates 1 and 2 is formed of a steel ribbon of constant width, rolled around the pillar about which it can rotate; an extended part of this ribbon has two ears 5 (Figure 4) bent 40 at right angles to the ribbon, as shown in Figures 1 to 3 so as to form a clasp with elastic limbs, acting as a holding member. This member could instead be independent of the proper distance piece.

45 The combination of the distance piece and the holding member form a species of clasp of which the two ears 5 engage in the recesses 6 and slots 7 formed in the plates. The bottom of the recess in the plate 2 has

50 a hollow 8 forming a retaining notch in which engages the corresponding ear of the clasp which is thus maintained locked for assembling the plates.

The method of using this embodiment is easily understood. The pillar being forced 55 into the plate 1, the clasp is first slipped over the pillar and then the plate 2, the clasp being finally closed by rotating same about the pillar so that its ears are turned over the plates. By employing a sufficient 60 number of such devices, the two plates are assembled in a perfectly positive manner. For disengaging the plates, it is only necessary to open the clasp.

The clasp being closed, none of the parts 65 of the device illustrated project beyond the limits of the plates, owing to the recesses 6 and slots 7 in which are located the ears 5.

The described device can be made by stamping out a steel lamina of the profile 70 shown in Figure 4, the part 4 then being rolled and the two ears 5 bent as shown in the other figures.

The described device has great advantages 75 over certain known devices for the same purpose, in particular over those comprising a pillar with two shoulders against which the components are applied by nuts screwing onto the pillar, the distance between the two shoulders determining the distance between 80 the components. Among these advantages the following may be mentioned.

The pillar is formed of a single cylinder, 85 without milling or shoulders and drawn from a simple wire drawn bar.

The use of assembling screws, pins, washers, etc., is dispensed with.

No displacement of one of the components 90 relative to the other can take place, the holes receiving the pillar being produced exact in diameter and position by stamping.

The distance between the components is rigorously exact and regular, being determined by the width of the ribbon forming the distance piece; this width is perfectly 95 constant and regular, the ribbon being made by stamping.

The manufacture is very exact, very easy, 100 very economical, all shoulder turning operations being avoided and replaced by stamping operations which are more exact and less costly.

The assembly and disassembly of the components is very rapid, exact, easy and economical, etc.

The form and arrangement of the various

parts of the clasp can differ from those illustrated. The holding member can engage the components differently, projecting beyond their limits, etc.

5 What I claim is:

An assembling device for bridges, plates and the like in time piece movements, counting mechanisms and like apparatus, comprising in combination with a setting pillar between the components to be assembled a

combined distancing and holding clasp like member formed of one and the same steel ribbon with a rolled portion pivotally arranged around said pillar to constitute a distance piece and two spring ears to constitute a clasp adapted to be turned over said components. 15

In witness whereof I have hereunto signed my name this 29th day of April, 1926.

CHARLES ROSAT.
